ASH TRAY

John C. Cramer, Dayton, Ohio, assignor to Dayton
Coil Spring Co., Dayton, Ohio

Filed Feb. 12, 1971, Ser. No. 115,146

Term of patent 14 years

Int. Cl. D27—03

U.S. Cl. D85—2

Fig. 1

Fig. 2

*FIG. 3**FIG. 4*

FIG. 1 is a top plan view of an ash tray embodying my new design;

FIG. 2 is a side elevational view thereof;

FIG. 3 is a bottom view; and

FIG. 4 is an elevational view of the side opposite from that shown in FIG. 2.

I claim:

The ornamental design for an ash tray, substantially as shown.
